DESIGN FOR A BOTTLE

René Tricard, Paris, France, assignor to Lenthalic Incorporated, New York, N. Y., a corporation of New York

Application October 24, 1934, Serial No. 53,736

Term of patent 14 years

To all whom it may concern:

Be it known that I, René Tricard, a citizen of France, residing at Paris, France, have invented a new, original, and ornamental Design for a Bottle, of which the following is a specification, reference being had to the accompanying drawing, forming part thereof:

In the drawing of the bottle:

Figure 4 is a bottom view.

I claim:
The ornamental design for a bottle substantially as shown.

In witness whereof I affix my signature.

RENÉ TRICARD.
